UNITED STATES PATENT OFFICE.

KEITH J. VAUGHT, OF SAN DIEGO, CALIFORNIA.

FENCE TOOL.

Application filed March 30, 1927. Serial No. 179,606.

This invention has reference to a tool especially designed for use in constructing and repairing wire fences or the like, the primary object of the invention being to provide a tool so constructed that a staple may be removed and held thereby, to the end that the staple will not be lost or distorted while being removed.

Another object of the invention is to provide a tool of this character which may be used as a hammer or wire splicer, thereby providing a combination tool possessing unlimited utility.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

25 Referring to the drawing:

Figure 1 is a side elevational view of a tool constructed in accordance with the invention.

Figure 2 is a plan view thereof.

30 Figure 3 is an end elevational view of the tool.

Figure 4 is a view illustrating the tool as used for removing a staple.

Figure 5 illustrates the use of the tool as 35 a wire splicer.

Referring to the drawing in detail, the device includes a handle 5 and an integral head 6.

The head 6 includes a finger 7 which is 40 curved slightly rearwardly and tapered to a fine point 8 so that the device may be driven into a staple to remove the same, without danger of distorting the staple.

As shown, the tool is provided with a recess 9 adjacent to the handle 5, the recess defining an enlargement 10 on the inner surface of the finger 7, to the end that when the finger 7 is driven into a staple in the act of removing the staple, the curved surface of the enlargement will act to remove 45 the staple.

Secured to the handle at a point adja-

cent to the recess 9, is a spring finger 11, the free end thereof being bent upwardly as at 12 so that a staple may be guided into the recess. This finger acts as a retainer 55 for holding the staple to the head of the tool after the staple has been removed by the tool, thereby eliminating any possibility of the staple being lost while repairing a 60 fence.

The head is also provided with a circular enlargement 13 which may be struck by a hammer or similar tool in driving the finger in position behind a staple to remove the 65 staple. It will also be seen that the enlargement 13 may be used as a hammer, should it be desired to position staples with the tool.

The opposite end of the tool is flattened 70 and bifurcated providing a slot 14 to receive wires to be spliced in a manner as shown by Figure 5, with the result that as the tool is rotated around the wires, the wires will be twisted together in the formation 75 of the splice.

From the foregoing it will be seen that due to this construction I have provided a tool which may be conveniently carried and one which will be capable of use as a staple 80 puller, hammer or wire splicer.

It will further be seen that should the tool be used in pulling a staple which is tightly held within the post so that the removal of the staple by the usual prying action will be difficult, the head of the tool 85 may be struck in such a way as to cause the curved surface or the enlargement to pass under the staple, forcing the staple from its position.

90 I claim:

1. A tool of the class described including a handle, a head at one end of the handle, said head including a finger tapered to a fine point, said head having a recess adjacent to the handle to receive a staple, and means overlying the recess for holding a 95 staple in the recess.

2. A tool of the class described including a handle, a head at one end of the handle, said head tapering to a fine point and curved rearwardly, an enlargement formed on the inner surface of the head adjacent to the handle, said head having a recess formed 100

adjacent to the handle to hold a staple therein, and means carried by the handle and disposed adjacent to the recess to hold a staple in the recess.

3. A tool of the class described including a handle, a head embodying a finger tapering to a fine point, said head having a recess formed adjacent to the handle, said recess adapted to accommodate a staple, and

a spring finger on the handle and overlying the recess to grip a staple in the recess to prevent the staple from passing from the recess.

In testimony that I claim the foregoing as my own, I have hereto affixed my signature.

KEITH J. VAUGHT.
